UNITED STATES PATENT OFFICE.

GUILLIAM H. CLAMER, OF ATLANTIC CITY, AND JAMES R. WYATT, OF CAMDEN, NEW JERSEY, ASSIGNEES TO THE AJAX METAL COMPANY, OF PHILADELPHIA, PENNSYLVANIA, A CORPORATION OF PENNSYLVANIA.

ELECTRIC FURNACE HAVING RESISTOR DOME.

Application filed November 20, 1920. Serial No. 425,420.

To all whom it may concern:

Be it known that we, GUILLIAM H. CLAMER and JAMES R. WYATT, citizens of the United States, residing at Atlantic City 5 and Camden, in the counties of Atlantic and Camden and State of New Jersey, have invented a certain new and useful Electric Furnace Having Resistor Domes, of which the following is a specification.

10 Our invention relates to furnaces of a type which are capable of rotation or oscillation in use and of tilting transversely to the axis for pouring, if desired, and utilizes both the reflected and radiated heat from the upper 15 furnace walls upon the surface of the metal and subsequent direct contact of the pool with these "upper" walls as the furnace is rotated or oscillated.

20 The purpose of our invention is to provide for generation of the heat within the furnace wall over the charge by reason of the resistance offered by said wall to the passage of electric current therethrough.

25 A further purpose is to equalize the current and heat generation as nearly as possible throughout the entire wall.

30 A further purpose is to pass the electric current circumferentially about the wall in a single series passage or in oppositely directed parallel paths as preferred.

35 A further purpose is to apply electrical current to a radiating upper wall of a furnace by induction and to rotate or oscillate the furnace to rest the molten metal upon this heated wall without necessity for interrupting the inductive transfer of current.

40 A further purpose is to combine a type of fluid-resistor induction furnace with a heat-radiating domed roof, heated by the induced current.

Further purposes will appear in the specification and in the claims.

45 Our invention relates to the processes involved as well as to the structures suggested as among the means by which these processes can be carried out.

50 We have preferred to illustrate our invention by a few forms only among the many by which it may be carried out, selecting forms by reason of their simplicity, efficiency and practicability, and because at the same time they well illustrate the principles of our invention.

Figure 1 is a side elevation of one form of our invention. 55

Figure 2 is a broken end elevation of the furnace.

Figure 3 is a vertical central section upon line 3—3 in Figure 1.

Figure 4 is a section upon line 4—4 of 60 Figure 3.

Figure 4^a is a similar section of a form corresponding nearly to Figure 4.

Figure 5 is a section corresponding to Figure 1 but showing a second form of our 65 invention.

Figure 6 is a section of Figure 5 upon line 6—6 thereof.

Figure 6^a is a similar section corresponding nearly to Figure 6. 70

Figure 7 is a section corresponding to Figure 1 but showing a third form of our invention.

Figure 8 is a side elevation, partly broken away, of the structure seen in Figure 7. 75

Figure 9 is a section upon line 9—9 of Figure 10.

Figure 10 is a side elevation of the structure seen in Figure 9.

Figure 11 is a section corresponding to 80 line 11—11 of Figure 12.

Figure 12 is a side elevation, partly broken away showing the structure seen in Figure 11.

Figures 13 and 14 are a side elevation and 85 an end elevation, respectively, showing one way in which any of our furnaces may be tilted for end pouring.

In the drawings similar numerals indicate like parts. 90

Electric furnaces having a refractory lining which is heated by the electric arc and in which the furnace is oscillated or rotated to bring the charge in contact with the portion of the lining which has previously 95 constituted the dome and which has been so heated, are well known. A conducting lining heated by current applied at the ends or by Jablochhoff candles at the periphery is also old. It is our purpose to utilize the exposed portion of the furnace lining or a belt thereof above the charge as a conductor of electricity, preferably of the second class and to induce an electric current in it or directly conduct such a current to it at 100 105 points about its circumference so that the

entire or a very large part of the heat of the furnace is represented by the C^2R developed within this conducting lining.

As will be recognized, this requires that the conductor of the second class shall have a very high fusing point and that it shall have either a relatively small cross section or a relatively high resistance, or both in order that the power factor may be maintained. These conditions may be secured with a lining which is a poor conductor when cold but which improves greatly in conductivity as the temperature rises, and which we call a conductor of the second class. Two examples of such conductors are found in carborundum and graphite.

Throughout all the forms of our invention the intention is to pass the current of electricity circumferentially about the walls, or 20 belts or bends therein, either in a single path, (with the belts in multiple where more than one belt is used) in series, (by induction or by electrodes) or in multiple paths dividing about opposite sides of the furnace. Likewise in all of our forms the resistor lining or belt above the pool adds to the heat of the metal during the main melting or heating operation by radiation and reflection from or upon it but in the preferred manner of use the furnace is oscillated so that the metal flows over the heated wall or belt which had previously been above it, with or without separate heating as by an induction resistor channel. At the same time that the metal of the pool is being heated by the new portion of the lining or wall over which it then flows, this portion of the lining or wall is cooled somewhat by the metal of the pool and excessive heating is 40 avoided.

In all our forms we provide for the rotation or oscillation of the furnace in its entirety and for the heating of the furnace by heating the lining, including and in most 45 cases particularly, the dome or belt, by which we mean to include all of the conducting furnace wall above the pool of molten metal. We prefer not to have the ends lined with conducting material.

50 In the forms shown in Figures 1-6 we have applied the current by induction from an alternating current transformer threading the circuit, while in the remaining figures the current is applied directly to the 55 conductive lining.

Describing the forms shown by way of illustration and not by way of limitation:—

In Figures 1-4, the cylindrical furnace is enclosed within a metal supporting casing 60 or shell 16 which is circumferentially interrupted and insulated as at 17 to break up flow of current circumferentially about this shell. The shell covers not only the outer cylindrical surface but may also enclose the 65 ends at 18 nearly to the center, providing

for a passage way within which the central leg 19 of transformer 20 passes. This opening is large enough for the winding 21 of the transformer and the winding is protected by a heat insulating and electrically 70 insulating tube 22 for which the material known as electrobestos is suggested as suitable. Air spacing is provided at 23 about the transformer winding and the transformer is supported from the casing by 75 brackets 24, insulated from one or both of them.

The transformer is shown as of shell type and may be built up in any way that is suitable so as to provide for insertion of the 80 leg 19 through the furnace body.

Our invention is not directed toward the character of the filling and pouring used and has been illustrated in connection with both side and end filling and pouring, with a view 85 to pointing out the independence of the invention with respect to such features. Either of these could be applied to any of the forms. Their character can obviously also be greatly varied. Where the filling 90 and pouring take place from the side, as seen in the earlier views, the shell 16 may be interrupted at any suitable point to provide an opening closed by a plug 25 which may be held in place by a strap 26. With end pouring, the shell may be rotated freely without reference to the pouring opening while with side filling and pouring, the difficulty of properly sealing the opening will ordinarily make it more desirable to oscillate the shell 100 95 as distinguished from rotating it. Continuing the description particularly of Figures 1 and 2, but including matter applicable also to other figures, the shell is lined with a heat insulating and electric insulating material 100 105 27 next to the shell, for which SilOCel is suggested as suitable, and within this insulator is placed the lining 28 which is intended to receive and hold the charge.

This lining 28 (which may be one or more 110 belts if desired) is preferably of some material which is a conductor, though not a good conductor of electricity when heated but which is a non-conductor of electricity when cold, known in this art as a conductor of 115 electricity of the second class. For this purpose carborundum or graphite is suggested, either one of which is sufficiently refractory and sufficiently poor a conductor of heat at all times, to be raised to a high temperature 120 by the electric current in it, while offering enough resistance so that a high power factor may be maintained.

Alternating electric current may be supplied to the transformer in any suitable way, 125 which we have not considered necessary to illustrate.

In order that the furnace may be rotated, or more probably merely oscillated, in some forms without interference from the trans- 130

former, the entire furnace is supported within an outer drum made up of two flanged parts 29, 29' insulated from each other. Brackets 30 space the drum from the shell sufficiently 5 to give full air circulation between, and at the same time rigidly support the shell. Tracks 31 are provided upon this drum and bear upon grooved rollers 32.

In operation the molten metal forms a 10 pool 33 in the bottom of the furnace and additions to the charge are put in through the opening 34 closed by plug 25. The current induced by the transformer passes through the conducting lining alone above the bath, 15 and the combined bath (if it be electrically conducting) and lining below its level. Since the resistance of an electrically conducting bath will be quite low, the heat generation will take place almost wholly in the 20 conductive lining or belt above it, raising the lining or belt to incandescence and heating the bath at first chiefly by radiation. However, turning the furnace in either direction brings a section of highly heated conductor-lining beneath the pool and exposes 25 the section upon which the pool has rested. This newly-exposed section then becomes heated by the induced current and the action continues as before.

30 As the furnace is rotated or oscillated, it will be noted that new portions of the lining are lifted above the pool to progressively and automatically receive major concentration of current.

35 In Figure 4^a a plurality of belts of conducting material 28^a are substituted for the lining of conducting material, as may be done in any of my forms in order to reduce the cross section and improve this power

40 factor. In the form shown in Figures 5 and 6 we have combined the advantage of a molten inductor furnace with the structure previously described. We have enlarged the 45 furnace chamber at one side so that the shell 16', refractory lining 27' and secondary conductor 28' conform to the enlargement and provide an axially extending trough 35. Within this trough the protective tube 22 50 for transformer leg 19' defines a resistor channel 36 for molten metal between the tube and the shell, completely surrounding the shell and communicating with the pool as best seen in Figure 5.

55 In this furnace the extra weight of the lateral extension is compensated by a lobe 37 upon the opposite side of the furnace and the entire construction is mounted to provide a track and wheel support of the same 60 character as that seen in Figure 3.

In the position shown in Figure 5, a complete secondary path is formed through the bath and the greater part of the secondary current will short circuit above into and 65 across the metal of the pool. Some part will

flow through the conductive (dome) lining or belt, and the proportion of current through each may be predetermined to make this useful or negligible in this position as desired. However, if the furnace be oscillated until the molten metal has left any part of the channel 36, substantially all of the current flow will take place through the conductive lining forming the dome. In this changed position of the furnace the current 70 passing through the pool itself would be equivalent to that merely which passes through the pool in the form shown in Figure 3.

The resistor channel may extend in an 80 axial direction the full length of the furnace, as in Figures 5 and 6, or a part of this length only, as may be desired.

This form in Figures 5 and 6 is, therefore, capable of use in either way, to operate 85 as in the first form, or to operate as an induction furnace of the molten resistor channel type. It may also be designed to use the resistor channel at all times, taking advantage of the heat-radiating capability of 90 the dome.

In this latter use the furnace offers special advantage in the case of materials which are poor conductors of electricity or non-conductors, in which case the current passes 95 through the conductor 28' chiefly if not entirely, heating it to a high degree. About the channel this heat conductor comes in contact with so thin a layer of the molten content as to heat it more rapidly than it heats 100 the pool and the heat transfer takes place through Joule circulation, or a combination of pinch and Joule circulation.

In Figure 6^a the channel width is reduced in width as at 36^a and the band at the top 105 is correspondingly narrower than the dome of Figure 6 to reduce the cross section and improve the power factor.

In the form shown in Figures 7 and 8, the current is applied directly from the 110 source of supply (which may be alternating or direct current) to the lining 28² by means of leads 38, 38' and conductors 39, and, entering the lining, divides and flows in multiple through opposite sides of the lining 115 from the one conductor to the other. In the illustration the points of application of the current are shown as at the top and bottom, in the normal position of the furnace, so as to heat both sides of the conducting 120 wall as nearly equally as possible, above the pool. However, as the furnace turns, wherever the conductors are located, there will be times when the current does not divide uniformly and when one part of the 125 dome or belt is consequently more highly heated than another. The conductors 39 may be placed at any point or points along the length of the cylinder desired.

The operation of this form is quite simi- 130

lar to that of the first form with the difference, however, that the current at all times passes through the two opposite parts of the conductive lining in multiple.

- 5 In the form shown in Figures 9 and 10, the current is applied to the lining or belt by means of a number of conductors 39' of copper or any other suitable material, here shown as connecting at their inner ends with 10 the lining 28² and as united to and sustained by commutator bars 40 at their outer ends. These commutator bars are engaged by brushes 41 mounted in supports 42, 42' and spring pressed at 43 for the purpose and 15 with the effect of leading the current in at approximately the same points relatively to the metal pool at all times, providing a sufficient number of commutators to secure any closeness of approximation to this which 20 may be desired. The brushes are here applied at the top and bottom so as to divide the current nearly equally about the walls of the dome.

Two sets of brushes are shown, one at each 25 end, suiting to the use of two phase current in separate belts, if desired, in the same manner that the three belts of Figure 4^a adapt it to use with three phase current applied to the separate belts, if desired, through the 30 use of three sets of contact brushes, similar in their connection to Figures 9 and 10, connecting with the three belts, instead of using the transformer seen in Figure 4^a. At the same time it is recognized that these 35 forms having a plurality of belts, instead of a dome, are well suited to connection of the current by brushes from a direct current of single phase current and with the several belts connected in multiple.

40 The operation of this form is substantially the same as that in the form shown in Figures 7 and 8, but secures a more uniform division of current about the walls above the pool.

45 In the form shown in the Figures 11 and 12 the conductive lining 28³ or belt is not continuous about the circumference but is interrupted at the top by insulation 44 and the edges are connected to terminals 39² fed 50 from leads 38. The same opportunity for use of a plurality of belts in multiple or with multiphase supply exists herein, and, indeed, in all of my forms.

55 In this form the electric current is fed directly through the entire circumferential extent of the conductive lining or belt in series, with the same division of current, however, between the lining or belt and pool throughout that portion of the lining upon which 60 the pool rests. In operation this closely resembles the inductive form shown in Figures 1-4, in that the current passes throughout all of the dome or belt and above the pool in series and equally whether the distance

from either electrode to the pool be small or 65 great.

In Figures 13 and 14, the same general form of furnace and electrical connections therefor are shown as in Figures 9 and 10 with a single commutator only, however, instead of the two commutators of the latter figures. These figures are given to show an adaptation of one of our forms of the furnace to end filling and pouring, with 70 recognition by us of the fact that any form of our invention might be applied in this manner or in various other ways to secure 75 end filling and pouring.

Our furnace of whatever form, in regard to the remainder of the structure—in this case corresponding generally to Figures 9 and 10—may be provided with an end filling opening typified at 45 and with an end pouring spout 46 which may be so placed as to allow complete rotation of the furnaces when 80 desired with bodily tilting for pouring purposes.

85 The construction which we have shown for accomplishing this comprises a platform 47 upon which the entire furnace and track 90 31 are mounted, and the rollers 32 with their supporting structure. The platform is shown as comprising side rails 47', supported about bearings 48 in brackets 49, the axis of the bearings being preferably in line 95 with the end of the pouring spout; so as to maintain the position of the pouring spout as the platform and furnace carried thereby are swung about the bearings 48. The platform is counterbalanced through chains 50 100 and counterweights 51.

We have not believed it to be necessary to complicate the figures by showing positive means for rotating the cylindrical furnace body about its axis—such means being 105 common, for example in circular racks and pinions. The end of the platform may be lifted for pouring by chain 52 engaging sprockets 53 upon shaft 54 which carries 110 sprocket 55.

In order to avoid complication of the tilting by possible rotation of the furnaces about their own axes, we clamp the furnaces tightly before tilting, as by brake-bands or straps 56 which may be held fixedly at either end, or may be tightened at both ends, as shown. In the tightening, the ends of the bands are secured about off-center pins 57 operated by handles 58 which are shown in tightened positions in Figure 14 to hold the 115 furnace tightly while tilting takes place.

We recognize that the lining itself comprises a belt of greater axial extent only than the narrow belts shown in Figures 4^a and 6^a, and we, therefore, use the expression 120 "lining or belt" in the claims for the purpose of indicating a belt which may be either narrow, forming a lining for a part only of

- the interior (usually cylindrical) surface, or may have sufficient axial extent to form the entire cylindrical surface with which the pool may come in contact, i. e., forming a complete dome. 65
- 5 We recognize that our invention may appear in various other forms than those shown, depending upon the needs of individual installations and the training or even 10 the whim of the designer and in the light of our disclosure and we intend to include herein all such forms and variations as fall within the fair spirit and scope of our invention. 15
- 15 Having thus described our invention, what we claim as new and desire to secure by Letters Patent is:—
1. An inductive electric furnace, comprising a chamber having an annular electrical conductor with which the pool is adapted to engage at the bottom and which is adapted to overlie the pool at the top in the form of a dome, and a transformer therefor having one leg passing through the electrical conductor. 20
  2. An electric furnace having an electrically-conductive dome or belt above the pool through which the operative electric furnace current passes and whose conductor resistance as connected as distinguished from resistance due to spacing of the parts, in conjunction with the pool develops the effective heat of the furnace from the C²R energy expended therein. 30
  3. An induction furnace having an electrically-conductive dome above the pool and included in the secondary transformer circuit. 35
  4. In an electric furnace adapted to contain a pool of molten metal, a casing, means for turning the casing about a longitudinal axis, a refractory insulation protecting the casing, a conductor of the second class forming a lining or belt within the insulation and means for passing electric current circumferentially through the conducting lining or belt and generating the entire heat of the furnace by the C²R conversion within the lining or belt and the pool of current into heat. 45
  5. In an electric furnace adapted to hold a pool, a casing having a longitudinal axis, mounting for turning the casing about the longitudinal axis, a refractory within and protecting the casing, a conductor of the second class forming a lining or belt within the refractory and adapted to come in contact with the pool, and a transformer having one leg passing through the conductive lining or belt and adapted to induce current circumferentially in it. 55
  6. In an electric furnace, a metallic casing interrupted to prevent flow of electric current thereabout and having a longitudinal
- approximately horizontal axis, mounting to support and guide the casing so that it may be turned about the axis, a refractory within and protecting the casing, a substantially cylindrical conductive lining or belt on the pool side of the refractory, comprising a conductor of the second class and means for passing electric current in series from the top to the bottom through the conductive lining or belt. 70
7. In an electric furnace, a metallic casing having a longitudinal axis, mounting to support and guide the casing so that it may be turned about the longitudinal axis, a refractory within and protecting the casing, a substantially cylindrical conductive lining or belt on the pool side of the refractory, comprising a conductor of the second class and a transformer having one leg passing through approximately the axis of the conductive lining or belt. 75
8. In an electric furnace, a metallic casing having a longitudinal axis, mounting to support and guide the casing so that it may be turned about the longitudinal axis, a refractory for the casing, a substantially cylindrical conductive lining or belt on the pool side of the refractory, comprising a conductor of the second class and a transformer having one leg passing through approximately the axis of the conductive lining or belt and adapted to rotate with it. 80
9. In an electric furnace, a metallic casing having refractory insulation therein and an electrically conductive lining or belt within the insulation intended to lie partly above and partly beneath the pool level, in combination with a transformer therefor having a leg extending through the conductive lining above the intended level of the pool. 85
10. An induction furnace, comprising an annular electrically-conductive band, a support therefor, mounting to permit turning of the band and support and a transformer within the band adapted to pass current through it. 90
11. In an induction furnace, a closed conductor adapted to form both a hearth and a dome therefor, a support for the conductor, mounting permitting turning of the conductor to vary the portion effective as a hearth and transformer means for passing electric current through the conductor. 95
12. In an electric furnace, a metallic casing, having refractory insulation therein and a conductive resistor within the insulation extending both above and below the intended pool level and separated axially into several parts by insulation, in combination with means for passing current through the separated resistor parts in multiple. 100
13. The method of operating furnaces by 105
- 110
- 115
- 120
- 125

electricity which consists in providing a resistor for the electric current above and also below the intended pool level and inducing electric flow of current through the resistor 5 circumferentially to heat the resistor above the pool level.

14. The method of operating an electric furnace which consists in providing a resistor for the electric current in the form of a 10 lining or belt above the pool and extending beneath the pool, in passing current by in-

duction through said resistor circumferentially to heat the lining or belt to a greater extent than the portion below the pool and in turning the resistor to pour the pool over 15 a new section of the resistor at one side while exposing a new section thereof at the other side of the pool and while maintaining inductive passage of electricity through the resistor.
